UNITED STATES PATENT OFFICE.

PHILIP P. MELANSON, OF MONCTON, NEW BRUNSWICK, CANADA.

ROOF-BRACKET.

1,340,492.

Specification of Letters Patent. Patented May 18, 1920.

Application filed October 23, 1919. Serial No. 332,720.

To all whom it may concern:

Be it known that I, PHILIP P. MELANSON, a citizen of the Dominion of Canada, residing at Moncton, in the Province of New 5 Brunswick and Dominion of Canada, have invented a new and useful Roof-Bracket, of which the following is a specification.

It is the object of this invention to provide a roof bracket of novel form, so constructed that an operator may work on the roof of a building, it being possible for workmen to work on the ends and the sides of the building.

The invention aims to improve generally 15 and to enhance the utility of devices of that type hereinafter described and claimed.

With the above and other objects in view, which will appear as the description proceeds, the invention resides in the combination 20 and arrangement of parts and in the details of construction hereinafter described and claimed, it being understood that, within the scope of what is claimed, changes in the precise embodiment of the invention 25 shown can be made without departing from the spirit of the invention.

In the accompanying drawings:—

Figure 1 shows in perspective, a building whereunto the device forming the subject 30 matter of this application has been applied; Fig. 2 is a side elevation of the roof bracket; Fig. 3 is a plan of the roof bracket; and Fig. 4 is a cross section on the line 4—4 of Fig. 3.

The device forming the subject matter of this application includes a base strip 1 provided at its upper end with an angular extension 2 constituting a supporting member. Brackets 3 are secured to the base strip 40 1, it being understood that there may be any desired number of these brackets on the base strip. The base strip 1 is provided at its lower end with a suspension device, preferably in the form of a hook 4. Plates 45 5 are secured to the base strip 1 at intervals, the plates being equipped with inner hooks 6 and with outer hooks 7. An angular arm 8 is connected at its inner end to the base strip 1 adjacent the upper end of 50 the base strip. Adjustable supports, such as screws 9, are threaded into the base strip 1 at spaced points, the screws being supplied with feet 29.

The numeral 10 denotes a roof of a building, the ridge pole appearing at 11. The base strips 1 are mounted on the roof 10

near to the ends thereof, the extensions 2 engaging the ridge pole 11. Although the base strips are shown as applied to one slanting surface of the roof, only, it will be understood that both slanting surfaces of the roof may be equipped with base strips, after the manner of the showing of Fig. 1. The inner hooks 6 of the base strips 1 are connected by flexible elements 12, the angular arms 8 engaging the edges of the roof 10. Thus, the base strips 1 are prevented from sliding toward or away from each other. Ledge pieces 19 may be mounted in the brackets 3, and, thus, the entire surface of the roof 10 may be shingled, painted or operated on otherwise. Boards 14 or the like may be placed under the feet 29 of the screws 9, and, thus, the strips 1 may be elevated from the roof 10 so that it will 70 be possible to paint, shingle, or work otherwise under the base strips. Boards 15 may be located on the roof and adjacent to the eaves, and over these boards may be trained ropes 16, the boards 15 serving to prevent 75 the ropes 16 from breaking the shingles at the eaves. The ropes 16 may be used to support a scaffold or the like, on which operators may work at the sides of the building. The outer hooks 7 of the base strips 80 1 on opposite sides of the roof may be connected by a rope 17 or other flexible element, and from the rope 17, any suitable means 85 18 may depend, for the support of a scaffold or the like, whereby operators may 90 work at the ends of the building. To prevent the rope 17 from breaking the shingles at the ends of the roof 10, boards 25 may be placed beneath the member 17. Before the ledge pieces 19 have been assembled 95 with the brackets 3, the brackets may be used to enable a person to ascend the roof 10. It will be seen that the device forming the subject matter of this application is so constructed that it will be possible to work on 100 both slanting surfaces of the roof 10, to work on the sides of the building, and to work on the ends of the building. A large gang may work at once on practically all of the exposed parts of the building.

Having thus described the invention, what is claimed is:—

1. In a device of the class described a base strip provided at its upper end with a supporting member; a bracket on the base strip 110 and means carried by the base strip for raising and lowering the base strip.

2. In a device of the class described a base strip provided at its upper end with a supporting member; an angular arm projecting from the base strip adjacent to the upper 5 end thereof; a bracket on the base strip; and means for raising and lowering the base strip.

3. In a device of the class described, a base strip provided at its upper end with a supporting member; a screw threaded into the 10 base strip and constituting means for raising and lowering the base strip; and a bracket on the base strip.

4. In a device of the class described, pairs 15 of base strips, the strips of each pair having oppositely projecting supporting members adapted to hook over the ridge pole of a roof; first scaffolds supported from the lower ends of the strips of the different 20 pairs; angular outstanding arms on the

strips and adapted to engage the ends or a roof to prevent the strips from moving inwardly when the scaffolds swing; a connection uniting the strips of each pair; second scaffolds suspended from the connections 25 and disposed substantially at right angles to first scaffolds; brackets on the base strips; ledge pieces mounted on the brackets; and connections uniting the strips of the different pairs to prevent a separation 30 thereof and a dislodging of the ledge pieces under the weight of the second scaffolds.

In testimony that I claim the foregoing as my own, I have hereto affixed my signature in the presence of two witnesses.

PHILIP P. MELANSON.
